UNITED STATES PATENT OFFICE.

ROBERT C. EDDY, OF MILWAUKEE, WISCONSIN.

DESIGN FOR A RUBBER BALL.

50,652.

Specification for Design.

Patented Apr. 24, 1917.

Application filed September 20, 1913. Serial No. 790,951. Term of patent 14 years.

To all whom it may concern:

Be it known that I, ROBERT C. EDDY, a citizen of the United States, residing at Milwaukee, in the county of Milwaukee and State of Wisconsin, have invented a new, original, and ornamental Design for Rubber Balls, of which the following is a specification, reference being had to the accompanying drawing, forming part thereof.

The figure is a plan view of a rubber ball showing my new design.

I claim:

The ornamental design for a rubber ball, as shown.

ROBERT C. EDDY.
